United States Patent Office.

JULES CONVERS, OF PARIS, FRANCE.

Letters Patent No. 82,805, dated October 6, 1868.

IMPROVEMENT IN MAKING CRANK-SHAFT.

The Schedule referred to in these Letters Patent and making part of the same.

TO ALL WHOM IT MAY CONCERN:

Be it known that I, JULES CONVERS, of No. 4 Rue de la Paix, Paris, in the Empire of France, chief engineer of the French and American Transatlantic Company, have invented a new and improved Arrangement Applicable to the Main Shafts of Steam and other Engines, giving to such shafts a much greater solidity, and considerably increasing their duration; and I do hereby declare that the following is a full, clear, and exact description thereof, reference being had to the accompanying drawings, and to the letters of reference marked thereon.

The main shafts of locomotive, marine, and other engines, the shafts of which are of the cranked description, and of which the wrists for the connecting-rods are forged together with the cranks, most frequently break at the joining-line of the wrist with the crank-arms.

The annexed drawing will convey to the mind the idea of my invention.

Figure 1 is a front view of a cranked shaft for the transatlantic steam-vessel "Saint Laurent," of nine hundred-horse-power, drawn to a scale of one-tenth, in which the collar is shown in section.

Figure 2 is a cross-section of the same shaft, through the line X Y.

When unsoundness of the cranked part of a shaft begins to show, it is produced by a small crack in the rounded angle which unites the wrist A to the arm B. This crack, which is at C, inside of the arm, widens, the oil penetrates, and the shaft in a short time becomes unfit for work.

This effect is produced because the fibres of the iron are forcibly cut off between the arms, when forging such shafts, and of course they are not fit to sustain firmly the violent shocks the shaft is supporting.

Instead of forging the wrists together with the arms of cranks, it was tried to introduce separate wrists in the eye of said arms, and fastening them tight by keying; but wrists so adjusted move after a while, and the centre going no longer true, the engine cannot work well.

The object of my invention is to obviate this serious inconvenience.

I forge the cranked shafts, as usual, in a single piece, with wrists and arms, and when finished, I bore in the centre of the wrist a hole which must be accurately true, and in such hole I introduce a central iron or steel wrist, D, which is prepared for this purpose, and the fibres of which cannot have been cut off by the arms, as the outside wrist which surrounds it.

This internal wrist or reinforce will have all the strength required to resist the clipping motion, and, owing to its envelope, it will have no tendency to shake away.

To fit it in place, it can be cooled, and the socket-collar heated, or a hydraulic press may be used to force it in.

The usual means will be used to secure it in position—a shoulder, E, and either a screw-nut or keys, F.

The annexed drawing exhibits, as aforesaid, on a scale of one-tenth, a shouldered internal wrist, inserted in the centre of the wrist, forged with the crank-arms of the main shaft of a nine-hundred-horse-power engine, intended for the steamship "Saint Laurent," to ply between Brest and New York. The internal wrist may be either concentric or not with its casing or outer wrist. In either case it must be calculated, as well as its casing and crank-arm, according to the force it will have to resist.

The same arrangement may be likewise applied to the stock G of the shaft, at its junction with the arms B of the crank.

But it is chiefly for the wrist of the cranked shaft that my improved system offers great advantages, for even if a crack were to break out in the outside collar, it would not be very important, and would find itself stopped by the inside wrist, which runs no danger of strain or rupture, and can stand any binding or twisting movement which the shafts may have to sustain.

What I claim as my invention, and desire to secure by Letters Patent, is—

The improved method, herein described, of making crank-axes, by forging them first, as usually done, in one solid piece, then boring the shouldered parts thereof, and strengthening the same by introducing separate pins, D, of steel or other strong material, embraced entirely within the metal, as and for the purposes herein set forth.

JULES CONVERS,
Rue de la Paix, 4, Paris.
